[57] CLAIM

The ornamental design for a lamp, as shown and described.

DESCRIPTION

FIG. 1 is a perspective view of a lamp, showing my new design;

FIG. 2 is a top plan view thereof;

FIG. 3 is a right end elevational view thereof, the left end elevational view being a mirror image thereof except for the representation of the bird;

FIG. 4 is a rear elevational view thereof;

FIG. 5 is a perspective view of a second embodiment of a lamp;

FIG. 6 is a top plan view thereof;

FIG. 7 is a right end elevational view thereof, the left end elevational view being a mirror image thereof except for the representation of the bird;

FIG. 8 is a rear elevational view thereof;

FIG. 9 is a perspective view of a third embodiment of a lamp;

FIG. 10 is a top plan view thereof;

FIG. 11 is a right end elevational view thereof, the left end elevational view being a mirror image thereof except for the representation of the bird; and

FIG. 12 is a rear elevational view thereof.

The broken line showing of the burner and mantle assemblies in FIGS. 1, 3, 4, 5, 7, 8, 9, 11 and 12 is for illustration only.

FIG. 1.

FIG. 2.

FIG. 3.

FIG. 4.

FIG. 5.

FIG. 6.

FIG. 7.

FIG. 8.
